[57] CLAIM

The ornamental design for an outdoor telephone booth, as shown and described.

DESCRIPTION

FIG. 1 is a front perspective view of an outdoor telephone booth showing our new design, the underside of the shelf being flat and unornamented;

FIG. 2 is a rear perspective view thereof;

FIG. 3 is a front elevational view thereof;

FIG. 4 is a side elevational view taken from the right of FIG. 3, the side opposite being a mirror image thereof;

FIG. 5 is a top plan view thereof.

The dotted areas in FIGS. 1 and 3 are intended to represent acoustical material and are understood to repeat uniformly across the circumscribed surface.

7.1 7.1.

7.2 7.2.
